UNITED STATES PATENT OFFICE.

ELLA CARDELL, OF CHICAGO, ILLINOIS, ASSIGNOR OF ONE-HALF TO ALICE SHIFFER,
OF MECHANICSVILLE, IOWA.

ADJUSTABLE MARKER.

1,163,505.

Specification of Letters Patent.

Patented Dec. 7, 1915.

Application filed March 17, 1915. Serial No. 15,032.

To all whom it may concern:

Be it known that I, ELLA CARDELL, a citizen of the United States, residing at Chicago, in the county of Cook and State of Illinois, have invented a new and useful 5 Adjustable Marker, of which the following is a specification.

The present invention relates to measuring and marking devices, and is particularly 10 an improvement over the adjustable marker disclosed in my Patent No. 1,111,212.

The object of the invention is the provision of an adjustable marker of the nature disclosed in said patent, and which is 15 provided with improved features, to enhance the utility and efficiency of the device, and render the device as simple in construction as is possible consistent with the utility thereof, and in order that the 20 cost of manufacture of the device will be reduced to a practical minimum.

One of the specific objects of the invention is the provision of unique means for applying an upright measuring stick or 25 bar to a table, bench or other support, and whereby the bar or stick will be held firmly upon the floor or base, so that the bar or stick which carries the marking elements may be employed by a seamstress for hanging 30 her own garments.

With the foregoing and other objects in view which will appear as the description proceeds, the invention resides in the combination and arrangement of parts and 35 in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein—

Figure 1 is a side elevation of the device in erected position. Fig. 2 is a perspective view of the member for attaching the measuring bar or stick to the table or other support. Fig. 3 is a perspective view of another form of attachment for fastening the measuring bar or stick to the table or support. Fig. 4 is a perspective view of another modified form of attachment. Fig. 5 is a perspective view of still another form of attachment.

In carrying out the invention, reference

being had to Fig. 1, there is employed a measuring stick or bar 1 which is graduated suitably, and which comprises upper and lower sections 2 and 3, the adjacent ends of which are detachably connected, whereby 60 when the device is not in use, the measuring stick sections may be detached so that the device can be compactly stored or carried. The measuring stick may be divided into various numbers of sections, and the sections 65 may be detachably connected in various manners.

The coupling illustrated in Fig. 1 embodies a sheet metal coupling member 4 of rectangular cross section for receiving the 70 adjacent ends of the sections 2 and 3 which are of rectangular cross section, and one side of the coupling member is provided with two pairs of slits 5 extending a short distance from the ends of the coupling member, and providing spring tongues 6 which bear against the measuring stick sections 2 and 3 for holding the sections and coupling member assembled, and to enable the parts to be readily assembled and detached. 75

An attachment 7 is employed for applying the measuring stick or bar to a table or other support T, when the measuring stick is disposed upright and seated upon the floor or base, and whereby the measuring 80 stick is firmly held in place. This attachment comprises a doubled resilient wire 8, the limbs of which are bent to provide the coils or loops 9 between the intermediate portion and ends of the wire, and to provide the curved or bent portion 10 between the loops or coils 9 and the central or intermediate portion of the wire. The end portions 11 of the wire project from the coils or loops 9 to that side away from the portions 10 and provide resilient arms to engage under the edge portion of a table or other support. The arms 11 are provided at their free ends with upturned teeth or spurs 12. A transverse strip 13 is secured 85 between the portions 10 adjacent the loops or coils 9, and has its ends coiled or bent around the portions 10, as at 14, whereby the strip 13 braces the wire element, and also serves as means for engaging one side 90 of the measuring stick or bar, with the loops or coils 9 straddling or overlapping the adjacent sides of the stick or bar. The strip 13 in connection with the intermediate portion of the wire and the portions 10, pro- 95

1-0

vide a binding element 15 slidable upon the measuring bar or stick 1. A thumb piece 16 is preferably secured to the intermediate or central portion of the wire 8. When the attachment 7 is applied to the measuring stick, the binding element 15 embraces the stick, or the stick is passed through the said element. Then, when the stick 1 is properly placed upon the floor, the attachment 7 is slid upwardly so that the arms 11 engage under the table or other support T, the teeth 12 biting into the table to prevent slipping, and then by forcibly raising the binding element 15, the arms 11 and coils 9 will be brought under tension, as well as the binding element 15. This will cause the binding element 15 to grip or bind upon the stick 1, to hold the attachment 7 and stick in place relative to one another, and the parts being brought under tension, will tend to move the stick 1 downwardly, and this will hold the stick firmly in place upon the floor or base. This is due to the reason that the binding element 15 being moved upwardly to bring the wire element under tension, will swing the binding element into gripping relation with the stick, and will spring the arms 11 and loops 9 so that they have a tendency to move the stick 1 downwardly relative to the table or support T. Consequently, the attachment 7 enables the stick 1 to be firmly fastened to the table or support T.

Upper and lower slides 18 and 25 are carried by the stick 1. The upper slide 18 is adjustable upon the measuring stick, and has a chalk or crayon holder and a spring tongue 23 for holding the chalk or crayon 24 in place and to allow the chalk or crayon to be adjusted, or removed for purpose of replacement. The lower slide 25 has a chalk or crayon holder 26 resembling the holder 22 above described.

The present device is used in the same manner as set forth in my former patent, *supra*, and a reiteration of the uses of the present device is therefore deemed unnecessary, since reference may be had to the said patent. Attention is directed, however, to the fact that the attachment 7 enables the measuring stick to be applied to the table or support T in a simple, but thoroughly efficient manner, for firmly holding the measuring stick upon the floor or base, whereby the measuring or marking operation may be carried out satisfactorily, the present device enabling the seamstress to measure or lay out her own garments. The device may also be employed as a trammel for laying off or marking the goods when laid upon a table or other surface.

In Fig. 3, a modified form of attachment is delineated, this attachment, designated 27, comprising a doubled resilient sheet metal member 28 having the apertures 29

for the measuring stick 1 adjacent the bend thereof, and having the projecting leaf springs 30 and 31 which are adapted to straddle the table or other support T, so that when the leaf springs 30 and 31 are placed astride the table or support they will be separated and will thus cause the member 28 to bind or grip the measuring stick for holding the measuring stick firmly in place.

Fig. 4 illustrates another form of attachment. This attachment 31 comprises a U-shaped clip 32 adapted to be placed astride the measuring stick 1 from one side, so that the attachment may be readily applied to and removed from the measuring stick without interfering with the marker slides 17 and 17'. This attachment 31 embodies the spring arms 33 having the terminal teeth or spurs 34 to engage the table or support, and the butt ends of the arms 33 are connected by a yoke 35 which is secured to one side of the clip 32 so that the arms 33 will be carried by the clip. It is evident that when the clip 32 is engaged to the measuring stick, it may be moved upwardly to engage the arms 33 with the table or support to bring the arms 33 under tension, the clip 32 will be caused to bind against or grip the measuring stick, the same as the attachment 7.

The attachment 36 illustrated in Fig. 5, is bent from a wire, and its intermediate portion is bent angularly upward as at 37, and the wire is provided with crossed portions 38 between the portion 37 and the ends of the wire. The spring arms 40 project from the crossed portion 38 and are provided with terminal teeth or spurs 41 to engage the table or support. The binding element 39 is provided between the portions 37 and 38, and is adapted to engage the measuring stick and to bind thereon when the binding element is lifted to cause the arms 40 to engage the table or support and spring, the same as with the attachment 7.

The present device may not only be used by dressmakers and seamstresses, but may also be found useful for many other purposes, as will suggest themselves.

Having thus described the invention, what is claimed as new is:

1. In a device of the character described, a bar adapted to be set on end upon a floor or base, and an attachment embodying means slidably engaging the bar and means for engaging under a table or other support, the attachment being of such construction that when the last mentioned means engages the table or support, the first mentioned means is caused to grip the bar and the bar is thereby held upon the floor or base.

2. In a device of the character described, a bar adapted to be set on end upon a floor or base, and an attachment embodying a resilient member having a binding element

slidably engaging the bar and having a portion to engage under a table or other support for causing the binding element to grip the bar and for holding the bar upon the 5 floor or base.

3. In a device of the character described, a bar adapted to be set on end upon a floor or base, and an attachment embodying a binding means slidably engaging the bar 10 and resilient means for engaging under a table or other support, whereby when said resilient means is brought under tension it will cause the binding means to grip the bar and will hold the bar upon the floor or base.
- 15 4. In a device of the character described,

a bar adapted to be set on end upon a floor or base, and an attachment embodying a binding element slidably engaging the bar and a resilient portion carried by the binding element and engageable under a table 20 or other support for causing the binding element to grip the bar and for holding the bar upon the floor or base.

In testimony that I claim the foregoing as my own, I have hereto affixed my signature in the presence of two witnesses.

MRS. ELLA CARDELL.
